UNITED STATES PATENT OFFICE.

HENRY F. REED AND SAMUEL KELLER, OF NEW YORK, N. Y.

DESIGN FOR A FOUNDATION-PIECE FOR CUT FLOWERS.

SPECIFICATION forming part of Design No. 18,785, dated December 4, 1888.

Application filed September 13, 1888. Serial No. 285,315. Term of patent 7 years.

To all whom it may concern:

Be it known that we, HENRY F. REED and SAMUEL KELLER, both of the city, county, and State of New York, have invented and produced a new and original Design for a Skeleton Foundation-Piece for Cut Flowers, &c.; and we do hereby declare that the following is a full and exact description thereof, reference being had to the accompanying drawing and to the letters of reference marked thereon, making a part of this specification.

Our design relates to a skeleton foundation-piece as a support for leaves and cut flowers. Said design consists, as represented in the accompanying drawing, of the outlines of a butterfly on the wing, as shown at A, from the center of which radiate two downwardly-diverging lines, B B, which are intersected below the butterfly by transverse curved lines C C, converging to a point, D, at one end, and connected

at the other by a line, E, to present the outlines of a cocoon or chrysalis open at the end. These lines convey to the eye in their combination as described the idea of a butterfly just escaped from the chrysalis.

25

We claim as our invention—

The design for a skeleton foundation-piece for cut flowers herein shown and described, the same comprising the outlines of a butterfly on the wing, the outlines of a cocoon or chrysalis beneath the same, and connecting-lines extending from the one to the other.

In testimony whereof we have signed our names to this specification in the presence of two subscribing witnesses.

HENRY F. REED.
SAMUEL KELLER.
